MEANS FOR COOLING PRINTING-ROLLERS.

1,153,398.

Specification of Letters Patent. Patented Sept. 14, 1915.

Application filed July 20, 1914. Serial No. 851,909.

To all whom it may concern:

Be it known that I, DANIEL E. LYNCH, a citizen of the United States, residing at Chicago, in the county of Cook and State 5 of Illinois, have invented certain new and useful Improvements in Means for Cooling Printing-Rollers, of which the following is a specification.

In the operation of high speed printing 10 presses it becomes necessary, especially during the summer season, to cool the ink feeding and distributing rollers, as otherwise the composition of which they are formed becomes soft, flaccid and loses the suction 15 properties upon which the efficiency of the rollers largely depends, and the rollers are liable to break down and fly to pieces resulting in jamming of the machinery of the press and consequent damage. It has been 20 proposed to effect this cooling by means of fans or by an air blast from other sources. It is also necessary to provide cushioning means whereby to absorb the momentum of the reciprocatory bed of the press at each 25 extreme of its stroke, and for this purpose dash pot mechanism has been employed. Where an air blast has been utilized to cool the inking rollers an expenditure of power and pneumatic installation has been 30 involved and where dash pot mechanism has been availed of to cushion the press at its change in direction of movement the energy thus generated has been wasted.

The object of this invention is to utilize 35 the air compressed in the one case to perform the useful function of the cooling fans in the other and thus effect a material saving in cost of installation and operation and of the space which would otherwise be 40 required for the operation of the cooling devices. I accomplish this object by leading the compressed air from the dash pot devices to a suitable expansion chamber where it is permitted to expand, thus lowering the 45 temperature, and then conduct the cool air to a suitable point of discharge upon and over the inking rollers. Thus the air compressed in the dash pot mechanism, instead of being wasted as heretofore, is utilized to 50 effect the cooling of the inking rollers without the necessity of installing a special blowing system and furnishing power to drive the same.

In order that the invention may be readily understood a preferred embodiment of the same is set forth in the accompanying drawing and in the description based thereon, wherein the same is shown and described as installed in connection with a typical form of printing press. As, however, the constructional features of the invention would be modified within a wide range to conform with the requirements of the particular installation the drawing and description are to be taken in an illustrative and not in an unnecessarily limiting sense.

As illustrated the press is indicated generally at 11 and includes a reciprocatory bed 12, and the ink feeding and distributing rolls 13 and 14. The press is shown as 70 equipped with a dash pot mechanism including the cylinders 15 and 16 fixed to the frame and adapted to receive at each stroke of the bed the piston members 17 and 18 carried by the latter whereby the bed is 75 cushioned at each extreme of its stroke. This construction is well known and further detailed description is considered to be unnecessary.

From the closed end of the cylinder or 80 dash pot 15 leads an air conducting pipe 19 and from the closed end of the dash pot 16 leads a similar pipe 20. The pipes 19 and 20 are provided with non-return check valves 21 and 22 respectively and beyond 85 these check valves a pipe 23 leads to an expansion tank 24. From the expansion tank a valved pipe 25 conducts the expanded air to the branches 26 and 27 the former of which terminates in a header 28 and nozzles 90 29 and 30 which discharge the air over and upon the inking rollers 13, while the pipe 27 leads to the header 31 and the nozzles 32 and 33 whence the air is discharged over and upon the inking rollers 14.

It is believed that the operation of the device will be obvious from the above description. Assuming the bed 12 of the press to have completed its movement to the left, as illustrated, the air within the dash pot 15 100 is compressed and forced past the check valve 21 into the expansion chamber 24 where it expands and is thereby cooled. Upon the reverse movement of the press the piston 18 compresses the air within the cylinder 16 and the compressed air is forced 105

through the pipe 20 past the check valve 22 to the expansion chamber 24 where it is permitted to expand and cool. The expanded cooled air is then blown through the 5 pipes 26 and 27 to the headers 28 and 31 and discharged upon the inking rollers by virtue of the pressure of the air constantly supplied to the expansion tank by the successive reciprocatory movements of the 10 press so that a substantially constant supply of air flows from the discharge nozzles upon the inking rollers and maintains the same at an appropriate temperature.

By my invention, not only is the air compressed in the cushioning of the bed utilized in the cooling of the rollers and an economy thus effected, but it has been demonstrated in practice that the cushioning efficiency of the dash pot mechanism is itself greatly enhanced and the shock attendant upon reversal of the bed movement minimized, the resiliency of the air cushion being increased by its extended distribution through the 15 pipes and the compression tank, and the wear on the pistons and the gearing and other working parts appurtenant to the bed 20 is thereby reduced. In addition to preventing the rollers from melting, the continuous flow of air keeps the form rollers, distributing rollers and ink plate free from dirt, lint and nap that paper always gives off and which settles around the bands of the press as well as on the inking rollers, and as a 25 result the forms do not have to be scrubbed. It also keeps the rollers free from all 30 particles of dirt, dust and bronze powder. Moreover, the flow of air from the dash pots may be utilized to supply the air jets now used in connection with feeding and 35 delivery mechanism for the automatic registering of sheets and the like.

I claim:

1. The combination with a moving body associated with elements subject to heating, of a nozzle arranged to discharge an air 45 current on the heated elements, means operated by the moving body to cause a flow of air through the nozzle, and means to modify the temperature of the air in its passage to the nozzle. 50

2. The combination with a reciprocatory bed of a printing press, and the inking rollers coöperating therewith, of pneumatic means arranged to cushion the reciprocatory bed, a system of air pipes leading from the 55 pneumatic means and discharging onto the inking rollers, and means interposed in said system to lower the temperature of the air.

3. The combination with a reciprocatory bed of a printing press, and the inking 60 rollers coöperating therewith, of dash pot mechanism arranged to cushion the reciprocatory bed, a system of air pipes leading from the dash pots and discharging on to the inking rollers, and means to lower the 65 temperature of the air after leaving the dash pots.

4. The combination with a reciprocatory bed of a printing press, and the inking 70 rollers coöperating therewith, of dash pot mechanism arranged to cushion the reciprocatory bed, a system of air pipes leading from the dash pots and discharging on to the inking rollers, and an expansion tank 75 interposed in the air conducting system.

In witness whereof I have hereunto signed my name in the presence of two subscribing witnesses.

DANIEL E. LYNCH.
